UNITED STATES PATENT OFFICE

GERARD VULTEE, OF DETROIT, MICHIGAN, ASSIGNOR TO DETROIT AIR CRAFT CORPORATION, A CORPORATION OF MICHIGAN

DESIGN FOR AN AEROPLANE

Application filed October 21, 1930. Serial No. 37,334. Term of patent 3½ years.

To all whom it may concern:

Be it known that I, GERARD VULTEE, a citizen of the United States, residing at Detroit, in the county of Wayne and State of Michigan, have invented a new, original, and ornamental Design for Aeroplanes, of which the following is a specification, reference being had to the accompanying drawing, forming part thereof.

Fig. 1 is a view in side elevation of my new aeroplane.

Fig. 2 is a top plan view of the same.

Fig. 3 is a view in front elevation of the same.

What I claim is:

The ornamental design for an aeroplane as shown.

GERARD VULTEE.
